H. W. HIGLEY.
SANITARY DISH WASHER.
APPLICATION FILED FEB. 9, 1920.

1,362,533.

Patented Dec. 14, 1920.

Inventor:
Herman H. Stigley

UNITED STATES PATENT OFFICE.

HERMAN W. HIGLEY, OF YONKERS, NEW YORK.

SANITARY DISH-WASHER.

1,362,533.

Specification of Letters Patent. Patented Dec. 14, 1920.

Application filed February 9, 1920. Serial No. 357,444.

To all whom it may concern:

Be it known that I, HERMAN W. HIGLEY, citizen of the United States, and a resident of Yonkers, in the county of Westchester 5 and State of New York, have invented certain new and useful Improvements in Sanitary Dish-Washers, of which the following is a specification.

The object of my invention is to provide 10 a dish washer employing both a running stream of water and a pliant rubber scraper, conveniently arranged to work in conjunction with one another, so that the operator or user may employ either the water or 15 scraper, or both. The water may be first applied, for the removal of all loose substances, while the scraper may be employed during the same operation in rubbing and scraping the dried and hard particles, with the flowing 20 water used as an assistant.

In this combination I provide means convenient to the operator or user for the manipulation of both water and scraper, and both are necessary in the removal and 25 cleansing of food stuffs from the utensils.

The water alone does not provide proper means for removing the hard and dried particles, such as dried egg, syrups and other hard drying food stuffs, which have to be 30 subjected to agitation in addition to the water to loosen and remove the same.

In my invention I provide a nozzle attached to a flexible tube, for conveying the water, that will condense the water into a 35 stream of a thin, uniform width and thickness under pressure. The stream, to cover as large a surface as possible, is arranged thin and wide, with means for maintaining the shape or form into a solid flow of water 40 about one sixty-fourth of an inch in thickness and two inches wide at the nose of the nozzle. The stream gradually increases in width as it leaves the nose. An object is to maintain an even force of the flow across the 45 entire width, without spreading or separating in particles from the main stream, keeping and maintaining the entire width of the stream or flow effective for quick and practical results. The water is transmitted from 50 the nose of the nozzle in a condensed sheet form, resembling a sheet of glass in appearance, flowing uniformly the entire width and thickness.

In other similar devices of this character 55 trouble is experienced in maintaining a stream of suitable shape in a uniform width

and thickness across the entire surface of the stream. In my improvement I employ means for condensing the water in such a manner that an even and uniform 60 flow is provided. These condensers are arranged in the nose of the nozzle, shaping the course of the water so that the stream holds together in a flat sheet within a fixed distance from the nose of the nozzle. In this 65 manner I overcome the disadvantages of a loose, irregular stream, as discharged from the nose of a nozzle without the use of condensers.

In addition to the stream or water flow as 70 outlined I employ a rubber band attachment, for use as a scraper in removing the remaining substance the water flow does not wash away. Owing to the elasticity of the rubber it will clean both smooth and irregular 75 surfaces with equal effectiveness, and owing to its pliability may be worked into crevices and uneven surfaces with rapidity, removing all substances from the even and uneven surfaces alike, when the scraper is 80 used in a rubbing or scraping movement over the matter to be removed. During the rubbing and scraping movement the water flow is being applied from the nose of the nozzle, the water softening the substance 85 during the rubbing operation.

The scraper forms an important part of my invention, as other devices depending solely upon the water flow, hot or cold, have proved impractical in general use. Without 90 means to agitate the dried particles of food, the water does not possess sufficient dissolving properties to remove the hard particles, and therefore does not wash anything but the loose substance away. 95

By the addition of the scraper in connection with the water flow, the scraper being used for removing the hard and dried particles, I overcome the disadvantages of other similar devices, and this together with an 100 improved stream or water flow of a uniform width and thickness, constitute the important features of my invention.

I attain these objects by means of the mechanism illustrated in the accompanying 105 drawing, in which,—

Figure 1 is a plan view showing the nozzle attached to the flexible tubing with a sheet of water being discharged from the nose.

Fig. 2 is the same view as No. 1 omitting 110 the water stream and rubber scraper, showing the condensers on both sides.

Fig. 3 is an end view looking directly into the nose of the nozzle.

Fig. 4 is a sectional view at *a—a* Fig. 2.

Fig. 5 is a side view showing the thickness of the stream of water being discharged.

Similar numerals refer to similar parts throughout the several views.

The nozzle is composed of two parts 1 and 2, which are soldered together at the joint 10 or seam 3, as clearly shown in Fig. 5, and correspond in shape and form with each other. The parts 1 and 2 are pressed from thin metal, so that when joined together at the seam 3 leave a water chamber 4, Fig. 15 4, within the shell, of the shape and form of the outside of the parts 1 and 2, less the thickness as shown throughout the drawings.

The round shank 5 with the securing bands 6^a, 6^b and 6^c, provide means for attaching and securing the flexible hose for conveying the water to the water chamber within the nozzle. The water flow is fed 20 from a faucet, through the flexible hose 7 25 to the opening in the shank 5 engaged with in the hose.

With the hose connected to the faucet or water supply, the water will first pass through the hose to the opening in the shank, 30 then to the water chamber in the main body 8 of the nozzle, passing on until it reaches the condensers 9, at which point it moves slightly inward toward the center of the nozzle, traversing the length of the condensers 10, and there passes from the nozzle in the shape of the stream shown at 11 in the drawing.

It will be observed in Fig. 5 that the water chamber 4 is gradually reduced from 40 the inlet shank 5 directly to the nose 12 of the nozzle, where the opening 4, Fig. 3, or the nose of the nozzle is arranged. The nose 12 of the nozzle is made rounding to assist in regulating the flow of the stream 45 to the proper thickness, which according to that arranged is about one sixty-fourth of an inch thick, although the thickness may be varied to meet necessary requirements.

The condensers 13^a and 13^b are formed by pressing the metal of the body parts 1 and 50 2 together at 14, closing the water chamber along the line and forming the condensers, as clearly shown at 15, Fig. 4. These condensers force the water in its flow into a solid mass that holds together after passing 55 from the nose of the nozzle, regulating the stream to a fixed and uniform width.

The rubber scraper 16, having a narrow flat, scraping surface 17, with beveled edges 18, is arranged to fit snugly and tightly 60 over the wider portion of the nozzle, near the nose 12, where it assumes a convenient position for use in combination with the use of the stream. The scraper 16 may be adjusted in separate pieces to both sides of the 65 body by means of rivets or otherwise. While the scraper is made with a narrow flat surface 17, and beveled sides, as a more practical form to be employed, a round, square or other form may be used with satisfactory 70 results.

Having thus described my invention, I claim:

1. The combination in a dishwasher of the character described of a nozzle having 75 a water chamber with a narrow opening at its outlet end, the walls of the nozzle converging on the sides and ends of said chamber to said outlet, and the sides being slightly convex at the outlet in the direction 80 of the flow of water and a rubber band attached to the nozzle near the outlet to be used as a scraper for removing any hard substance not easily affected by the stream.

2. The combination in a dish washer of 85 the character described, of a nozzle having a water chamber with a narrow opening at its outlet end, the walls of the nozzle converging on the sides and ends of said chamber to said outlet, and the sides being slightly 90 convex at the outlet in the direction of the flow of water.

Signed at Yonkers, in the county of Westchester and State of New York, this seventh day of February, A. D. 1920.

H. W. HIGLEY.
